UNITED STATES PATENT OFFICE

2,474,332

SPRAY NOZZLE

Carl C. Sciuto, St. Louis, Mo.

Application January 11, 1946, Serial No. 640,527

1 Claim. (Cl. 299—131)

1

This invention relates to improvements in spray nozzles of the type generally employed with garden hose.

An object of the invention is to improve the structure of spray nozzles to produce an efficient nozzle that is durable and efficient, and which may be economically manufactured.

Another object of the invention is to provide a device of the kind mentioned, which may be conveniently and accurately adjusted to throw a spray of varying spread and character, and which will substantially avoid a drip at the spray orifice, whereby the nozzle may be used without projecting a part of the stream vertically at the nozzle outlet, but which will project the stream away from the user of the nozzle.

Additional advantages inherent in the structure will appear from the following detailed description taken in connection with the accompanying drawing, in which:

Fig. 1 is an elevation of the nozzle;

Fig. 2 is a longitudinal sectional view through the device taken substantially on the line 2—2 of Fig. 1;

Fig. 3 is a cross-sectional view taken substantially on the line 3—3 of Fig. 2; and

Fig. 4 is a cross-sectional view taken substantially on the line 4—4 of Fig. 2.

In the embodiment of the invention illustrated in the drawing, the device is shown as including a base section A having a cylindrical body portion 1, the exterior of which is provided with spaced, annular knurled ribs 2 whereby it may be conveniently manually engaged and operated. The interior of the body portion 1 is formed with an internal annular recess 3, in which a washer 4 is seated. The interior of the body 1 is provided with a threaded section 5 forming a threaded socket adapted to be screwed upon the usual threaded hose terminal. The inner wall 6 of the member A has a central opening 7 therein, the walls of which are beveled outwardly.

A member B, constituting an internal conduit, is in the form of a hollow stem 8, having an internal bore 9 open at its inner end, but which terminates inwardly of its outer end. An outwardly flaring flange 10 is formed around the inner opening into the bore 9, which fits within the opening 7 in the wall 6 of the base member, and is connected into said opening to form a tight joint. The outer end of the member B is formed with a reduced cylindrical section 11 forming a recess. A head 12 is formed at the outer end of the stem 8. This head has a beveled face to the center of which a flanged stem 13 is in-

tegrally connected. Inwardly of the head 12, and at the outer extremity of the bore 9, are lateral orifices 14, which serve to direct the stream entering the inner end of the bore 9 laterally into the recess formed around the reduced portion 11 of the stem 8. The member B has a part of its exterior wall threaded, forming a threaded section 15.

The member B is also provided with an annular groove 16 positioned inwardly from the threaded portion 15, which groove is adapted to constitute the seat for a split ring 17. The walls of the ring 17 bevel outwardly. The ring constitutes a stop for the external barrel of the device. It also permits easy assembling of the stem with the exterior barrel, as will be hereinafter more fully described.

The external barrel member C comprises a generally cylindrical member 18, which is provided with a pair of spaced annular knurled ribs 19, one of which is at the inner end of the member C and the other of which is spaced outwardly therefrom, these knurled portions providing convenient means for engaging and rotating the barrel.

The member C is provided on its internal surface with a threaded section 20 complementary to the threaded section 15 of the member B whereby, when the member C is threaded over the member B, it will move longitudinally in respect thereof in both directions upon being rotated, as will be readily understood. The inner end of the member C is formed to provide an enlarged recess 21 in which is seated a packing ring 22, the outer face of which seats against a cupped metallic washer 23. The end of the recess 21 is threaded as at 24, and is adapted to receive in threaded engagement a complementary threaded screw plug 25, having a spaced spanner wrench recess 26 therein.

The outlet end of the member C is formed by an annular wall 27, the inner face of which is beveled toward the outlet orifice. The angle of the inner face of the wall 27 is formed at an angle complementary to the bevel of the outer face of the head 12. The outer face of the wall 27 is planar.

In assembling the device, the members A and B are integrally united, and the member C separately assembled by seating the packing ring 22 and washer 23 in the recess 21, which parts are held in place by tightening down the screw plug 25 to clamp the packing ring in position, the cupped washer 23 serving to expand the

packing ring radially inwardly against the stem 8, thereby forming a liquid-tight joint.

The member C is then slipped over the outer end of the member B and the threaded sections 15 and 20 interthreaded. The member C is then rotated to move it inwardly in respect to the member B and, as the washer 23 passes over the split ring 17, the ring 17 is compressed sufficiently by the contact of the beveled surface thereof with the internal surface of the washer to permit continued movement of the member C inwardly of the member B. The ring 17 then expands, and the high inner side thereof forms a stop, limiting the outer movement thereafter of the member C, in respect to the member B, to maintain the parts in operative and assembled relation.

The parts are so dimensioned that when the member C is in its innermost adjustment, as illustrated in Fig. 2, the outlet orifice of the nozzle is closed by the beveled wall of the head 12 contacting the inner beveled face of the wall 27.

As the member C is moved outwardly in respect to the member B by rotating the same, the liquid stream passing through the bore 9 enters the space between the reduced section 11 of the member B and the inner wall of the member C through the transverse orifices 14. As the beveled face of the head 12 is moved away from the inner beveled face of the wall 27, the passage-way to the nozzle orifice is valved to produce a stream annular in form, which is directed tangentially inwardly against the flanged stem 13. The stream is then deflected outwardly in a truncated cone-spray formation, the volume and spread of which may be varied by rotation of the member C.

The formation of the inwardly opposite beveled wall 27, in relationship to the beveled outer face of the head 12 together with the location of the flange stem 13, is effective to prevent downward drip from the spray orifice and to cause the body of the stream to be deflected outwardly away from the spray nozzle, the extent of spread and the fineness of the spray being accurately determined by the relative adjustment of the member C in respect to the member B. When the head of the stem 13 is beyond the plane of the outer face of the wall 27, the spread of the spray is in the formation of a cone having a wide base and the spray is finely dispersed.

As the space between the face of the head 12

and the inner face of the wall 27 is increased, and the head of the stem 13 moves into the plane of the outer face of the wall 27, the spread of the spray is reduced approaching a cylindrical form with increased volume whereby the outward projection of the stream is substantially increased.

From the foregoing description, it will be understood that the structure fully accomplishes the objectives hereinbefore stated.

It should also be understood that the invention is not limited to the structural forms of the elements, but that modifications within the scope of the claim may be made without departure from the invention.

What I claim and desire to secure by Letters Patent is:

In a spray nozzle, the combination with a hollow stem having a valve plug at one end and a recess in the periphery thereof, of a revolvable barrel enclosing said stem having interfitting threaded engagement therewith, whereby upon rotation of said barrel relative longitudinal movement in respect of said sleeve is imparted thereto, a wall at one end of said barrel forming an outlet orifice and providing a valve seat for said valve plug, a packing member carried by said barrel at the opposite end to said outlet orifice, said packing including a metal washer on its forward face, and a compressible split ring mounted in said recess in said stem having a frusto-conical surface, the greatest diameter of which faces said washer to permit movement of said barrel in one direction for the assembly of the stem and barrel, and limiting movement in the opposite direction after said members are assembled, the greatest diameter of said split ring being disposed opposite to said metal washer when said stem and barrel are in assembled relation.

CARL C. SCIUTO.
